UNITED STATES PATENT OFFICE.

GEORGE A BURNHAM, OF CLIFTONDALE, MASSACHUSETTS.

AUTOMATIC VOLTAGE-REGULATOR.

1,118,633.

Specification of Letters Patent.

Patented Nov. 24, 1914.

Application filed July 16, 1910, Serial No. 572,314. Renewed October 16, 1914. Serial No. 867,035.

To all whom it may concern:

Be it known that I, GEORGE A. BURNHAM, a citizen of the United States, and resident of Cliftondale, in the county of Essex and State of Massachusetts, have invented an Improvement in Automatic Voltage-Regulators, of which the following description, in connection with the accompanying drawings, is a specification, like letters on the drawings representing like parts.

To regulate the terminal voltage of generators, it is usual to vary the strength of the field current, and this has been accomplished by means of interrupting the field circuit of the generator, or by excluding and including periodically an additional fixed resistance in series with the usual field resistance.

When the entire field circuit is opened a powerful change of field strength is effected and vicious sparking or arcing results from the field discharge which renders these methods too heroic to be satisfactory in practice, and they have not therefore proven successful. When a fixed resistance in series with the field winding is employed the regulating devices must be of a character which will permit a delicate response to the conditions of the external circuit, otherwise the regulating parts will overshoot the proper degree of movement and fail in their intended effect in maintaining constant voltage.

My invention is designed to effect as prompt and sensitive a regulation as either method could afford without incurring the deleterious arcing from sudden and great changes of field strength and without incurring jerky and irregular regulator movements; I effect this by employing a make-and-break device constantly operating to shunt a moderate field resistance, said device constantly operating under powerful magnetic control which is extremely sensitive to minor voltage variations, and I provide a hand-switch for adjusting the field resistance to permit it to act to best advantage under wide ranges of load in the main circuit. Also I secure quick action for varying the proportion of the make with relation to the break, in the make-and-break device, by providing means independent of the voltage being regulated to coöperate with the voltage-responsive mechanism in giving the make-and-break device extreme

sensitiveness. The make-and-break device preferably consists of two contact members, one of which is responsive to two separate influences, one the changes in voltage in the main circuit which is being regulated, and the other independent of said changes in voltage. Preferably the make-and-break device is of the type in which one member contains a conducting section and an insulated section and is rotary, or at least continuously movable, at practically constant speed, and the other member has continuous vibratory movement with relation to said movable or rotary member, and I provide mechanism for varying the throw or vibration thereof, consisting of two separate means, preferably comprising an electromagnetic actuator and a quick-acting actuator, such as a spring, coöoperating with said electromagnetic actuator to give steadiness and quickness of make-and-break action and to prevent tendency of the vibrating member to overthrow or to be moved by the electromagnetic actuator beyond proper position and to remain in said improper position long enough to allow the voltage of the generator to rise abnormally.

My invention includes further points of advantage of construction and operation, which will be more fully pointed out hereinafter, in the course of the description of the mechanism.

In the drawings, I have shown diagrammatically a preferred embodiment of the invention.

For convenience of illustration, I have shown a generator 1 whose mains 2, 3 supply lamps or other translating devices 4. The field 5 of said generator is under the control of a rheostat or variable resistance 6, such as usually employed for regulating the voltage of a generator or the speed of a motor. The form of make-and-break device herein shown comprises a rotary cylinder 7 divided diagonally into a conductor section 8 and an insulated section 9, said cylinder being rotated by any suitable means, as by a motor 10, herein shown as supplied with energy from any suitable source, as for convenience supplied from the mains 2, 3 by conductors 11, 12. Coöoperating with the cylindrical contact member 7 is a brush contact 13 whose vibrating arm 14 is pivoted at 15. An arm 16 therefrom is connected at 17 to the core 18 of an electromagnet whose winding 19 may be supplied

with energy from any source of power, shown for convenience as connected to the mains 2, 3 by wires 20, 21, a resistance 22 being interposed in the wire 21. A spring 23 normally tends to overpower the electromagnet when deenergized or to hold the contact arm 14 in opposition to the electromagnet, and a dash-pot 24 is preferably provided to prevent too great an amplitude of movement of the arm 14 under the influence of said spring. A contact-making voltmeter serves to control the electromagnet, being herein shown as comprising an electromagnet 25 connected across the mains by conductors 26, 27 (a resistance 28 being interposed in the latter), the core 29 of said electromagnet operating a contact lever 30 pivoted at 31 and having a movable contact 32 to coöperate with a fixed contact 33 connected by a wire 34 to the conductor 21, the conductor 20 being connected by a wire 35 to said lever, preferably at the pivot 31 and said lever being normally held in practically floating or balanced position by a spring 36 so as to have extreme sensitiveness of make-and-break action in response to its electromagnet 25. This make-and-break action opens and closes a short-circuit for the brush operating coil 19, providing a powerful and sensitive adjustment for the brush which makes its action reliable under the drag of the rotary interrupter 9. Coöperating with the rotary contact member 7 is a brush 37 connected by a wire 38 to the arm 39 of the rheostat, the other terminal of the rheostat being connected by a wire 40 to the conductor arm 14 of the vibrating contact member, and a condenser 41 being connected across the wires 38, 40. The condition is preferably such that when the voltage is constant in the main line circuit, the contact-making portion of the voltmeter, *i. e.* the lever 30, is floating, by which I mean that the contacts 32, 33 are in such a sensitive or balanced relation that they may be said to be open or to be closed, as either relation may then exist. The result is that the arm 14 is maintained in a constant state of vibration as the cylinder 7 rotates. If now the load 4 is increased so that the voltage lowers in the main circuit, the contact 32 will be maintained closed, thereby demagnetizing the electromagnet 19, whereupon the spring 23 instantly tends to shift the brush 13 to the left, thereby momentarily increasing the duration of short circuit of the rheostat in the field circuit of the generator, which increases the current in the field and raises the voltage in the main circuit, and when said voltage reaches normal the contacts 32, 33 open, thereby energizing the electromagnet 19 and moving the brush 13 back to the right in opposition to the spring 23 and dash pot 24. This causes the rheostat to be short circuited for a shorter

duration at each rotation of the cylindrical contact member 7. The constant vibration or opening and closing of the contacts 32, 33 in response to the fluctuations of voltage in the main circuit maintains a corresponding constant vibration of the brush 13. 70

It is a well known fact that the current cannot rise instantly in the field circuit of the generator on account of its inductance. Consequently the arm 14 would move too far or overreach its proper position if said arm were equally balanced or floating, as would be the case if the arm were dependent for all its movement simply on the energizing and deenergizing of electromagnetic control, and accordingly to give quickness, sensitiveness, and accuracy of movement and prevent the effect of this overreaching or tendency to overreach, I provide the spring 23 (and preferably the dash pot 24) which tends at 80 all times to move the brush 13 and arm 14 to the left so as to give quickness in overcoming their movement to the right. This prevents the brush from remaining in the overreaching position (as it otherwise would 85 until after the voltage had changed again), whose effect on the field would be to cause the voltage to vary either above or below normal, thereby reacting again on the electromagnetic control of the brush to produce 90 an opposite, but slow and lagging, movement of the brush to an opposite abnormal or over-reaching position, where it would tarry until the sluggish field effects would produce another similar cycle of movements and effects, the latter being the well-known pumping effects, commonly experienced with one solenoid only which is energized directly from the mains. By my combination, I establish a vibration, which, notwithstanding 95 that its maximum in either direction extends to the improper position of the brush, is so quick in action that its over-reaching effect is practically lost or eliminated (because of its quickness of movement and the magnetic sluggishness of the field) and the operative influence thereof is simply that of the mean or intermediate half. The arm 14 and its brush are vibrated constantly even though the voltage is at normal, but inasmuch as the return movement is rendered 100 quick and instantaneous by the spring 23 the resultant current in the field is not determined by either of the extreme positions of the brush but by the intermediate or average 105 position. If the entire back and forth movement of the brush were determined solely by electromagnetic operating or shifting means, the time required to move the brush would be dependent upon the comparatively long length of time required for energizing and deenergizing the electromagnetic means, which is necessarily slow because of inductance and also because of the time required for the voltmeter to operate. 110 115 120 125 130

Whenever there is a change of voltage in the main line, the contacts 32, 33 either remain closed or remain open until the voltage has been restored in the main line. This results in changing the position of the brush 13 lengthwise of the cylinder 7 or in other words changes in voltage in the main line coöperate with the normal vibratory movement above explained, to produce a variable 10 vibration or variable length of vibration and also to cause the brush 13 to assume said different positions longitudinally of the contact member 7, thereby varying the duration of the break with relation to the duration of the make in the make and break device.

In further explanation of the importance 20 of my invention, I secure accuracy by employing the voltmeter therefor and power by employing the electromagnet therefor, as distinguished from attempting to provide both accuracy and power by means of the same electromagnet (still greater accuracy being secured by combining a spring action 25 with the power actuating electromagnet, as already explained), in connection with the continuous short circuiting of the field rheostat. By short circuiting this adjustable rheostat I eliminate the vicious and de-

structive sparking and also bring the intensity of sparking under the direct control of the operator, as already explained. 30

Having described my invention, what I claim as new and desire to secure by Letters Patent is,

In a voltage regulator, the combination of a generator having a shunt field, a constantly operating motor-driven interrupter in a shunt around a portion of the field resistance, said interrupter having an oblique 40 cylindrical contact to effect a variable interval of the shunt closure, a voltage magnet derived from the mains acting on the interrupter brush, a quick acting spring-retractor for the brush, a dash-pot to give a retarded 45 brush movement against the spring retractor, a voltage relay coil derived from the mains, and a floating contact operated thereby, said contact being included in a short-circuit around the brush operating coil. 50

In testimony whereof, I have signed my name to this specification, in the presence of two subscribing witnesses.

GEORGE A. BURNHAM.
